LITHOGRAPHIC PLATE GRAINING MACHINE
CLAMP

Martin G. Dunn, Washington, D. C.

Application December 3, 1946, Serial No. 713,690

5 Claims. (Cl. 51—6)

1

This invention relates to improvements in lithographic plate graining machines, and more particularly to hold-down devices for clamping the plates firmly and evenly upon the bottom of the grainer box or tub.

The general object of the invention is to provide a novel and improved plate clamp for graining machines which may be quickly applied and released, which is resilient in action, and which is easy to manufacture and install while at the same time being of sturdy construction and not liable to get out of order or require frequent repair or replacement.

In its preferred embodiment, the invention contemplates the provision of a spring pressed foot which, during operation of the machine, bears resiliently upon the margins of the lithographic plate being treated, either directly or through the intermediary of a flat hold-down strip. The spring pressure is released and the presser foot raised by means of a novel manually actuated lifting cam, for replacement of the plates between operations.

Other objects, including the provision of presser feet of resilient material and novel universal mountings for the presser feet, will be apparent from the following specification when read in connection with the accompanying drawings in which certain embodiments of the invention are illustrated by way of example.

In the drawings,

Figure 1 is a view in perspective of one end of the tub of a graining machine embodying the principles of the invention, the parts not being drawn to accurate scale but shown so as to best illustrate the construction and operation of the clamps;

Figure 2 is a fragmentary view in vertical section through one of the novel clamps, and taken transversely of the supporting cross-bar; the clamp being in raised position;

Figure 3 is a similar view showing the clamp in applied position; and

Figure 4 is a fragmentary vertical sectional view through a presser foot of alternative construction.

The grainer box or tub is indicated in the drawings by the reference numeral 10 and it will be understood by those skilled in the art that the tub 10 is mounted in a substantially horizontal position for rotary or gyratory movement in the horizontal plane. Means are also provided for loading the tub, after the lithographic plates are properly clamped therein, with the

2

steel balls or marbles and the wetted abrasive material, as is also well known in the art. The tub 10 is provided with an end wall 11, side walls 12, and a bottom wall 13 upon which is secured the rubber blanket 15. The margins of the rubber blanket 15 may be extended a slight distance along the side walls 11 and 12 as at 16 and are adapted to be held in position by the strips or slats 17.

10 Lithographic plates 20 which are to be grained are laid in orderly rows upon the blanket 15 on the bottom of the tub, and are adapted to be firmly retained in flat position to be acted upon by the abrasive under the influence of the rolling balls or marbles. These plates are of any familiar type, whether made of zinc, copper, or aluminum, or whether new or used. The object of the graining process is to prepare clean grained surfaces on the plates for the reception 15 of the lithographic image in the process of lithographic or offset printing. In the case of the treating of old plates, the object is to remove the old image from the surface of the plate so that the plate may be used over and over again.

20 Although the hold-down clamp may be applied directly to the corners or margins of the plates 20, it is preferred to cover the marginal edges of the plates with the hold-down strips 22 which are made of thin flexible metal and are preferably provided with bevelled or chamfered edges so that the balls may roll freely across their surfaces as well as upon the surfaces of the plates being treated.

The clamping arrangement comprises generally a series of cross bars 25 which are adjustably secured at their ends to the inturned flanges 26 of the side walls 12 of the grainer tub. The flanges 26 are preferably cut away adjacent the end of the tub so that the bars may be more readily removed when necessary. The cross bars 25 may be of any desired cross-sectional configuration, being made either in one piece or built up from simpler shapes such as flat strips, angles, or channels. However, for the purpose 35 of simplicity of illustration the cross bar in the drawings is shown as being of X-section having a pair of vertical flanges 29 and a pair of horizontal flanges 30. A transverse end plate 27 is formed or welded adjacent the ends of the cross bar 25, and exteriorly of that end plate there are provided spaced flanges 28, the lower ones of which may comprise essentially continuations of the horizontal flanges 30 of the cross bar. These spaced flanges are adapted to slidably receive 40 the flange 26 of the tub and the bar 25 is adapted

to be clamped into position by means of the set screw 32 which is threaded through the upper flange 28 and is adapted to bear downwardly upon the tub flange 26.

At selectable intervals along the cross bar 25, depending upon the width of the plates 20 and the consequent positioning of the strips 22, are disposed the novel hold-down clamps designated generally by the reference numeral 35. Each of these clamp elements 35 comprises a substantially rectangular block 36 which is kerfed as at 37 to receive one of the side flanges 30 of the cross bar 25. The kerf 37 is inclined slightly to the horizontal so that it may be made slightly wider than the thickness of the flange to which it is applied and permit a slight canting of the block 36 so that under pressure the block will assume a substantially horizontal position.

The block 36 is drilled vertically to provide a bore having an enlarged portion 38 for the lower part thereof and an upper portion 39 of slightly less diameter. The presser rod 40 passes through the opening in the block and surrounding this rod there is a coil spring 41, seated at its upper end against the shoulder 42 within the bore, and at its lower end against the pin 43 which passes through the rod 40. The rod is thus resiliently urged downwardly toward the bottom 13 of the tub 10.

The lower end of the rod 40 is threaded as at 45 to adjustably receive the presser foot 46. This foot 46 comprises a rubber block, preferably of cylindrical configuration, and provided with an opening or recess within which is secured an internally threaded bushing 47 to which the rubber is secured as by vulcanizing. It will be readily understood that the presser foot may be rotated upon the shaft and disposed in different positions of adjustment, thus in effect providing for the elongation of the rod 40, and accommodating it to the height of the layers or sheet material to be clamped, and to compensate for any wear on the presser foot. The presser foot 46 is adapted to bear resiliently upon the lithographic plates or upon the hold-down strips 22. The bearing pressure is made resilient both by means of the coil spring 40 and the resilient nature of the pressure block 46. The resilient deformable block 46 also permits the bottom surface of the presser foot to conform to the surface to which it is applied.

The release and lifting of the presser foot 46 is accomplished by means of the hand lever 50 which is bifurcated as at 51 and provided with a cross pin 52 passing through the bifurcations and through the upper end of the rod 40, which is straddled by the bifurcations. The edge surfaces 54 of the bifurcation 51 are provided with the proper camming configuration to effect the lifting of the presser foot by swinging the lever 50 about the pin 52. The applied position of the clamp is shown in Figure 3, and it will be noted that in this position the handle 50 occupies a substantially horizontal position. In Figure 2 of the drawings, the device is shown in its raised position wherein the handle 50 has been moved through an angle of approximately 90° and the nose of the cam surface 54 bears upon the upper surface of the block 36.

In order to maintain the hand lever 50 in its proper position of alignment when the presser foot is in applied position, there is provided a keeper device consisting of a split pin 55 set in an opening in the upper wall of the block 36 and adapted to have its split and somewhat re-

silent upper end received in the recess 56 drilled in the lower side of the lever 50. Within the broad purposes of the invention, this retaining means may assume a variety of different forms, the one selected for illustration being merely typical of numerous retaining means which may be employed.

In Figure 4 of the drawings there is shown a modified form of presser foot and rod in which the foot 46A is of metal and mounted for universal movement upon the lower end of the rod 40A. An opening 47A is drilled in the upper surface of the foot or block 46A, the bottom of the opening being preferably although not necessarily of a conical or roughly spherical shape as indicated at 47B. The lower end of the rod 40A is provided with an annular groove 45A within which a pin 46B is adapted to be somewhat loosely received. The extreme lower end of the rod 40A comprises the head or enlargement 45B which is preferably provided with a flat conical or spherical lower surface conforming roughly to the surface 47B of the opening 47A.

In this modification, the head 46A is provided with means affording universal rocking movement upon the end of the rod 40A whereby the bottom of the presser foot may find its proper bearing upon the strip 22 or the lithographic plates 20, regardless of variations in the position of the clamping device 35 on the cross bar 25.

In order to properly clamp the edges of the plates at the sides of the tub, similar clamps may be provided at intervals along the ledges or flanges 26 of the side walls 12 of the grainer tub.

It will be seen that the present invention provides means which marks a considerable improvement over the old clamping devices, the clamping pressure of which has generally been attained by screw clamps having no resilient features and being very time consuming in application and removal.

Various changes and modifications may be made in the embodiments illustrated and described herein without departing from the scope of the invention as defined in the following claims.

Having thus described the invention, what is claimed as new and desired to be secured by Letters Patent is:

1. In a lithographic plate graining machine, a grainer tub, a supporting member extending above and in spaced relation to the bottom of the tub, and at least one plate clamp carried by said member, said clamp comprising a body portion secured to said member, a presser foot depending from said body portion, means for urging said foot resiliently downwardly upon a plate resting upon the bottom of said tub, and manually adjustable cam means for raising said foot from operative clamping position.

2. In a lithographic plate graining machine, a grainer tub, a supporting member extending above and in spaced relation to the bottom of the tub, and at least one plate clamp carried by said member, said clamp comprising a body portion adapted to bear on said supporting member, a substantially vertical rod guided vertically with respect to said body portion, a spring for urging said rod downwardly with respect to said body portion, a presser foot on the lower end of said rod adapted to bear upon a plate on the bottom of said tub, a cam lever pivoted to the upper end of said rod and having a cam surface adapted to bear against said body portion, whereby upon swinging of the

lever the presser foot is cammed upwardly and the pressure on the plate released.

3. In a lithographic plate graining machine, a grainer tub, a supporting member extending above and in spaced relation to the bottom of the tub, and at least one plate clamp carried by said member, said clamp comprising a body portion adapted to bear on said supporting member, a substantially vertical rod guided vertically through an opening in said body portion, a coil spring compressed between stop portions on said body portion and said rod for urging said rod downwardly with respect to said body portion, a presser foot on the lower end of said rod adapted to bear upon a plate on the bottom of said tub, a manually actuated cam lever pivoted to the upper end of said rod and having a cam surface adapted to bear against the upper surface of said body portion, whereby upon swinging of the lever the presser foot is cammed upwardly and the pressure on the plate released.

4. In a lithographic plate graining machine, a grainer tub, a supporting member extending above and in spaced relation to the bottom of the tub, and at least one plate clamp carried by said member, said clamp comprising a body portion adapted to bear upon said supporting member, a substantially vertical rod vertically movable relative to said body portion and having a presser foot on the lower end thereof, means urging said rod and foot downwardly toward the bottom of the tub, a lever fulcrumed on said body portion and pivotally connected with said rod, whereby swinging movement of the lever in a vertical plane toward and from said body portion causes the rod to be moved vertically with relation to said body portion and said foot to be moved vertically relative to a plate on the bottom of said tub, against the influence of said urging means, a guide pin extending from the surface of said body portion and adapted to wedgingly enter a recess in said lever as it moves toward said body portion in approaching clamp applied position, whereby said lever is retained in said position until manually moved therefrom.

5. In a lithographic plate graining machine, a graining tub, a supporting member extending above and in spaced relation to the bottom mem-

ber of the tub, and at least one plate clamp carrying said member, said clamp comprising a body portion adapted to bear upon said supporting member, the substantially vertical rod vertically and rotatably movable relative to said body portion and having a presser foot on the lower end thereof, means urging said rod and foot downwardly toward the bottom of the tub, a cam lever pivotally mounted intermediate its length on the upper end of said rod and free to rotate therewith when not in clamping position, said lever having a camming end adapted to bear against the surface of said body portion as a fulcrum, whereby a swinging movement of said cam lever toward and from said body portion causes the rod to be moved vertically with relation to said body portion and said foot to be moved vertically relative to a plate on the bottom of the tub, against the influence of said urging means, a guide pin extending from the surface of said body portion and adapted to wedgingly enter a recess in said lever as it moves toward said body portion in approaching clamp applied position, whereby said lever is retained in said position until manually moved therefrom.
